BURNER FOR TORCHES

Frederick B. Embury and Alfred J. Perkins,
Warsaw, N. Y., assignors to Embury Manufacturing Co., Warsaw, N. Y., a corporation of New York

Application December 17, 1934, Serial No. 757,770

5 Claims. (Cl. 67—55)

This invention relates to highway flare torches for use as warning and safety lights in construction work and by motor busses and trucks when stalled on the highway and the invention has for 5 one of its objects to provide such torch with a burner of extremely simple and sturdy construction.

Another object of this invention is to so construct the burner that it efficiently protects its 10 flame in any kind of weather.

A further object of this invention is to so construct the burner that sudden shifts and increase in intensity of the wind will not affect the combustion of the fuel in producing the flame of the 15 burner.

Another object of this invention is to provide the burner with means whereby a number of torches can be conveniently collected and carried in one hand.

20 A further object of this invention is to so construct a one piece burner that it can be readily lighted and quickly and efficiently cleaned.

A further object of this invention is to provide the burner with flame openings which are arranged so as to provide at all times a protected 25 exit for the flame thru one or more of these flame openings.

All these and other objects and attendant advantages will become more readily apparent from 30 the detailed description of the invention which follows, reference being had to the accompanying drawing in which

Figure 1 is a top plan view of the burner.

Figure 2 is a longitudinal sectional view of 35 the burner as it appears mounted on and locked to the torch body, the section being taken on the line 2x—2x of Figure 1.

Figure 3 is a vertical sectional view thru one 40 of the flues of the burner, the section being taken on the line 3x—3x of Figure 2.

Figure 4 is a vertical sectional view of the wick 45 holder and combustion chamber of the burner, the section being taken on the line 4x—4x of Figure 2.

Figure 5 is the figures of the drawing like reference numerals indicate like parts.

The burner for highway flare torches forming the subject matter of our present invention is 50 adapted to be removably mounted to the neck 1 of the torch body or font 2. The neck is provided with a series of fixed locking cams 3, 3 which hold the burner clamped and locked to the neck 1 as will hereinafter be described.

55 The burner proper comprises a single piece casting to provide an extremely sturdy construc-

tion therefor. Aluminum has been found desirable for the burner casting because of its greater heat conductivity over other metals. The burner is provided with a base 4 surrounded by a flange 5 which carries on the inside the locking lugs 6, 6. 5 This base is attached to the body by telescopingly placing the flange 5 over the neck 1 and the locking cams 3, 3 thereof and then turning the base to have the locking lugs 6, 6 engage under the locking cams 3, 3 and have the cams draw the 10 base down onto the neck and hold it clamped thereto with a suitable washer 7 located between it and the base to provide a tight joint between them.

In the center the base 4 is provided with the 15 wick holder 8 which comprises a short vertical duct in which is held the wick 9 to keep its lower end suspended in the torch body thru the neck 1 thereof and keep its upper end projecting substantially half way into the dome 19 above the 20 wick holder. One or more spirally arranged ridges 11 within the wick holder serve to hold the wick in its proper position and provide for its adjustment up or down in the holder by simply rotating it in either one or the other direction. 25

The dome 10 extends horizontally over the wick holder and provides the combustion chamber for the burner. Air inlet openings 12, 12 are provided in the sides of the dome near the bottom thereof and are located on opposite sides of the 30 wick 10 in close proximity to the top end thereof in order to supply air thereto for the combustion of the fuel. The air inlet openings extend angularly thru the wall of the dome substantially radial to the wick and thus direct the air thereto. 35 As illustrated in Figure 4 the air inlet openings are also inclined downwardly away from the bottom of the dome so as to drain any rain water which may collect in the combustion chamber around the wick. 40

A pair of vertically arranged open ended flues 13, 13 are provided on the dome 10 and form a combustion chamber therewith. These flues are located on each side of the dome 10 and provide the flame openings in the top and bottom of the combustion chamber which prevent the wind from blowing directly thru the combustion chamber no matter from what direction it strikes the burner. The flames from the burner thus normally issue from the open top of each of the flues 13 and provide a vertical twin flame for the burner. Air is admitted thru the open bottom of the flues while the flames issue from the top thereof and furnish additional air for an effi- 50 55 55

cient combustion of the fuel in the combustion chamber.

When a high wind blows against one of the flues of the burner, it causes the flame to be forced out of the top and bottom of the other flue and vice versa. When a wind blows into the top of the flues, the flames are forced out thru the bottom thereof. In fact, no matter in what direction the wind blows against the burner, the combustion chamber is always protected against a direct draft therethru to prevent the blowing out of the flame of the burner while sufficient protected flame openings are provided to prevent a smothering of the flame.

15. Flames may thus issue from the top of both of the flues, the top and bottom of one or the other of them, or flames may issue from the bottom of both flues depending on the direction and intensity of the wind which blows against 20 the burner. The air which enters the burner thru one or both openings of one flue to cause the flame to issue from one or both openings of the other flue will in turn support the combustion in the burner and cause an efficient flame 25 to issue therefrom no matter thru what openings of the flues it leaves the burner. Under certain conditions flames may also be forced from the air inlet openings 12 so that the air for the support of the combustion of the fuel is taken entirely or practically so thru one or more openings 30 of the flue.

Rain will not affect the burning of the torch because the top of the wick is effectively shielded by its close proximity to the top of the dome 35 forming the combustion chamber. Any water entering the top of the flues will thus pass right thru the flues without entering the combustion chamber and the little that may seep into the combustion chamber from the flues is readily 40 drained therefrom by the air inlet openings 12, 12 which, for this purpose, as above pointed out, incline downwardly away from the bottom of the combustion chamber and thus prevent any collection of water in the combustion chamber 45 around the wick.

As illustrated in Figure 2 the burner is provided with handle means in the form of a chain 14 which is attached to the clip 15 anchored to the burner and carries a ring 16 at the outer end

thereof. The chain is of a suitable length which permits the chain of a number of the torches to be brought together and held together by the rings of the chains. This permits a number of torches to be held suspended from one hand and 5 collectively carried thereby.

We claim:

1. A burner for a torch comprising a wick holder, an open ended tubular dome extending horizontally over said wick holder to provide a combustion chamber with an opening at each end and open ended flues extending across the open ends of said dome with an opening in the side of the flues leading into the open ends of the dome. 15

2. A burner for a torch comprising a base, a horizontally arranged hollow body forming a combustion chamber and having a flame opening in the top and bottom substantially in line with each other, a wick tube leading into said combustion chamber to one side of said openings and spacedly supporting said combustion chamber above said base. 20

3. A burner for a torch as set forth in claim 2 including an air inlet leading into the side of 25 said combustion chamber adjacent to said wick tube.

4. A burner for a torch comprising a base, a horizontally arranged elongated hollow body forming a combustion chamber and having a flame opening in the top and bottom at each end thereof with the flame openings in the top substantially in line with the flame openings in the bottom, a wick tube leading into the bottom of 30 said combustion chamber between said flame openings and spacedly supporting said combustion chamber above said base to provide an unobstructed exit for the flames from the bottom of 35 said combustion chamber.

5. A burner for a torch comprising a base, a 40 horizontally arranged hollow body forming a combustion chamber and having a flame opening in the top and bottom at the ends thereof, a wick tube leading into the bottom of said combustion chamber between said flame openings and 45 spacedly supporting said combustion chamber above said base.
